2 SHEETS | SHEET 2.

UNITED STATES PATENT OFFICE.

THOMAS A. BIGGS, OF SIOUX CITY, IOWA.

CONTAINER CAR.

Application filed November 25, 1921. Serial No. 517,471.

To all whom it may concern:

Be it known that I, THOMAS A. BIGGS, a citizen of the United States, residing at Sioux City, county of Woodbury, and State 5 of Iowa, have invented a new and useful Improvement in Container Cars, of which the following is a specification.

This invention relates to container cars.

An object of the invention is to provide 10 an improved container system for rail transportation including a series of individual containers or tanks adapted for transportation upon railway cars or other cars designed therefor, and including a novel construction and arrangement for unloading the individual containers or tanks from the cars upon which they are carried.

Another object of the invention is to provide means for utilizing the force of gravity 20 for unloading the containers or tanks from the cars.

Another object of the invention is to provide a system of unloading and loading the containers or tanks by utilization of the 25 force of gravity for both purposes.

Another object of the invention is to provide an improved car for use in transporting a series of individual containers or tanks including individual supports for the containers or tanks, and means for inclining the supports individually for the purpose of utilizing the force of gravity in loading and unloading the containers or tanks.

Other objects of the invention will appear 95 from the following description, reference being made to the drawing in which—

Fig. 1 is a side elevation of the invention.

Fig. 2 is a plan view showing the aprons 40 at one side of the car extended outwardly to the positions they occupy when used for unloading purposes.

Fig. 3 is an end elevation of one of the containers, the car body being shown in section.

Fig. 4 is a diagrammatic view showing the 45 arrangement for utilizing the force of gravity in unloading and loading the containers or tanks.

Fig. 5 is an enlarged view showing the 50 pivoted arrangement of the aprons and the cams controlled thereby for supporting the pivoted plates or decks that carry the containers or tanks.

Fig. 6 is a similar view showing the apron 55 extended laterally to permit inclination of the plate or deck controlled thereby.

In the embodiment of the invention shown the body or frame of the car supports a shaft 1 mid-way between the sides thereof. A number of separate plates or decks 2 have 60 brackets 3 rigid with their undersides and pivotally mounted upon the shaft 1. In this way the plates or decks 2 are supported a proper height above the permanent bed of the car. About six inches of space between 65 the permanent bed of the car and the inclinable plates or decks is sufficient for most embodiments of the invention, though this space may be increased or reduced as desired without variation from the principle 70 of the invention.

A shaft 4 is supported above and near each side edge of the car body. A number of aprons 5 are pivoted to each of the shafts 4 and are movable to and from vertical position against the sides of the separate containers or tanks 6. The container tanks 6 are of any desired construction and material. Rollers 7 on horizontal axes support the tanks and facilitate the utilization 80 of the force of gravity in loading and unloading the container tanks upon and from the inclinable plates or decks 2; and rollers 7^a on vertical axes and operating against the sides of rails 7^b on the plates 2 guide 85 the tanks in loading and unloading and hold the tanks from shifting in transit. At each side of the several container tanks is a pivoted element 8 forming latches adapted to engage with and support the aprons 90 5 vertically against the side of the container tanks on the car, as shown.

By reference to Figs. 5 and 6 the construction and arrangement of the aprons 5 will be more clearly understood. As there 95 shown, each of the aprons 5 has an angular portion 9 at its lower edge pivoted upon the corresponding shaft 4. This arrangement is desired in order that when one of the aprons 5 is turned over to an inclined position, as shown in Fig. 4, the upper surface of said apron will form a continuation of the upper surface of the inclined plate or deck 2. When an apron 5 is inclined for loading or unloading purposes, the adjacent 100 edge of the inclinable plate or deck 2 is supported upon the flat upper surface of the angular portion 9, as clearly shown in Fig. 6.

Each end of the angular portion 9 of each 110 of the aprons 5 is provided with a cam comprising a portion 10 of short radius and a

portion 11 of long radius. The relationship of the parts is such that when the aprons 5 are raised vertically at the sides of the container tanks, the edges of the inclinable 5 plates or decks 2 are supported upon the cams 10 which are of short radius. When one of the aprons 5 is turned over to an inclined position, the projections 12 on the adjacent edge of the corresponding plate or 10 deck 2 drop to the flat upper sides of the integral cams 10 and 11; while at the same time the apron 5 at the opposite side of the container tank is swung downwardly to a position in which it is suspended from its 15 supporting shaft 4. This causes the long cams 11 in connection with the apron which is swung downwardly, as stated, to raise the adjacent side of the inclinable plate or deck 2 to move said plate or deck from its normal horizontal position to the inclined position shown by broken lines in Fig. 3. In 20 this position both side edges of the inclinable plate or deck 2 will be firmly supported, the upper edge upon the long cams 11 and the lower edge upon the flat upper sides of 25 the body of the cams 10 and 11 that are in connection with the inclined apron. This permits the container tank upon the inclined apron to move laterally under force 30 or impulse of gravity, the rollers 7 facilitating such movement.

As shown in Figs. 3 and 4, the inclined aprons 5 may be rested upon a movable platform 13 which is also inclined. 35 The system, as shown in Fig. 4, involves the idea and means of transferring container tanks from one car to another. The system there shown includes the movable platform 13 which receives upon its higher 40 end the apron 5 of the car from which the tank is to be moved. Gravity is utilized to move the container tank from the car over the inclined apron 5 and onto the movable or portable platform 13. The lower end of 45 the inclined portable platform will be in line with the upper edge of the tiltable platform or deck of the car onto which the container tanks are to be loaded, and in this way gravity is utilized throughout for unloading and loading of the container tanks 50 from one car to another. In Fig. 3 a motor truck 13^a stands on inclined ground or on an inclined platform or base to obtain the same result.

55 Each side of each of the container tanks is preferably equipped with a ring 14 or equivalent device for receiving a rope or cable to hold back and control the container tanks in their movements.

60 At the end of the bed or body of the car a part 15 is provided to prevent endwise movement of the container tanks. Preferably each car is made of the capacity to receive several of the container tanks in 65 slightly spaced relation, removable blocks

or wedges 16 being provided to hold the tanks spaced. When it is desired to remove any one of the container tanks from its car, the spacers 16 at the ends thereof are removed to permit free lateral movement of 70 the tank.

Each of the tanks may be equipped with L-shaped locks 17 to hold the tanks in position on the plates 2 until the aprons 5 are placed in inclined position and it is desired 75 to move the tanks from said plates 2. The locks 17 may be turned to position to engage the side edges of the plates 2 and thereby hold the tanks from movement until the locks are disengaged from said plates 2. 80

From the foregoing it will be seen that the present invention is designed and adapted to utilize the force of gravity in unloading and loading the container tanks. The container tanks may be respectively loaded 85 and unloaded without interference with the others since the inclinable plate or deck for each container tank is capable of independent control. The construction and arrangement may be varied in numerous particulars without departure from the nature and principle of the invention. 90

I do not restrict myself unessentially, but what I claim and desire to secure by Letters Patent is:—

1. A container car, comprising a body, a number of inclinable plates or decks pivoted above the longitudinal axis of the car body, means for moving said plates or decks to and from inclined position, and means for supporting the plates or decks in horizontal position. 95

2. A container car, comprising a body, a number of inclinable plates or decks pivoted above the longitudinal axis of the car body, 100 means for moving said plates or decks to and from inclined position, means for supporting the plates or decks in horizontal position, and a separate container tank removably mounted on each of said plates or decks. 110

3. A container car, comprising a car body, a number of inclinable plates or decks pivoted above the longitudinal axis of the car body, means for supporting the plates or decks horizontally above the car body, and 115 means for moving the plates or decks independently to inclined positions above the car body.

4. A container car, comprising a car body, a number of inclinable plates or decks pivot- 120 ed above the longitudinal axis of the car body, means for supporting the plates or decks horizontally above the car body, means for moving the plates or decks independently to inclined positions above the car body, a removable container tank supported 125 by each inclinable plate or deck, and means for holding the container tank in position on the inclinable plate or deck.

5. A container car, comprising a car body, 130

a number of inclinable plates or decks pivoted above the longitudinal axis of the car body, cams for supporting the side edges of the plates to maintain the plates in horizontal positions and being movable to position to permit the plates to be inclined, and means for inclining the plates.

6. A container car, comprising a body, a number of inclinable plates or decks pivoted above the longitudinal axis of the body, cams for supporting the side edges of the plates to maintain the plates in horizontal positions, means for moving the cams at either side of the plates to position to permit the adjacent side of the plates to lower, and cams for raising the opposite sides of the plates to incline the plates and to support the plates in their inclined positions.

7. A container car, comprising a car body, a number of inclinable plates or decks pivoted above the longitudinal axis of the car body, a container tank supported on each of said plates or decks, means for supporting the plates or decks in horizontal positions when the container tanks are on the plates, and means for moving the plates or decks to inclined positions to utilize the force of gravity in moving the container tanks onto or from the inclined plates or decks.

8. A container car, comprising a body, a number of inclinable plates or decks pivoted above the longitudinal axis of the car body, a container tank for each plate or deck, rollers for supporting the container tanks respectively on the plates, or decks, means for supporting the plates or decks in horizontal positions when the container tanks are there-

on, and cams for moving the plates or decks to inclined positions to utilize the force of gravity to move the container tanks from the plates or decks.

9. A container car, comprising a car body, a shaft supported longitudinally above the axis of the car body, a series of separately movable plates or decks pivoted to said shaft, cams on each side edge of the car body for supporting the plates or decks in horizontal positions, and being movable to permit inclination of the plates or decks, and cams for inclining the plates or decks.

10. A container tank system for rail transportation, comprising a car, a series of inclinable plates or decks pivotally supported by the car and adapted to be inclined downwardly toward either side edge of the car as desired, a container tank removably supported upon each plate or deck, a movable platform having an inclined upper surface, an inclinable apron supported by the car movable to position to rest upon the inclined top of the movable platform, means for raising the opposite side edge of the plate or deck to support the same in an inclined position corresponding to the inclined position of said apron and of said platform to utilize the force of gravity in moving the container tank from the inclined plate or deck, and an adjacently positioned car having its upper surface in substantial alignment with the lower end of the inclined surface of the movable platform to utilize the force of gravity in moving the container tank from the platform thereto.

THOMAS A. BIGGS.
